UNITED STATES PATENT OFFICE.

ANDREW J. MORRARTY, OF PROVIDENCE, RHODE ISLAND, ASSIGNOR TO MARTIN-COPELAND COMPANY, OF PROVIDENCE, RHODE ISLAND.

EYEGLASS-MOUNTING.

1,162,184.

Specification of Letters Patent. Patented Nov. 30, 1915.

Application filed April 30, 1914. Serial No. 835,348.

To all whom it may concern:

Be it known that I, ANDREW J. MORRARTY, a citizen of the United States, residing at Providence, in the county of Providence and State of Rhode Island, have invented 5 certain new and useful Improvements in Eyeglass-Mountings, of which the following is a full, clear, and exact description, such as will enable others skilled in the art 10 to which it appertains to make and use the same.

This invention relates to finger-piece eyeglass mountings, and with regard to certain 15 more specific features thereof, to operating springs therefor.

One of the objects of the invention is to provide a finger-piece mounting which is compact, simple and practical.

Another object of the invention is to reduce 20 the amount of strain upon the retaining member or screw.

The invention accordingly consists in the features of construction, combinations of elements and arrangement of parts, which 25 will be exemplified in the method herein-after disclosed and the construction herein-after set forth, and the scope of the application of which will be indicated in the following claims.

30 In the accompanying drawing, wherein is shown one of various possible embodiments of the invention, Figure 1 is a fragmentary plan view of a finger-operated eyeglass embodying this invention; Fig. 2 is a 35 view in elevation of Fig. 1; Fig. 3 is a perspective view of the operating spring enlarged; and Fig. 4 is a cross sectional view of the operating spring taken on the line 4-4 of Fig. 3.

40 Referring now more particularly to the drawing, wherein similar reference characters refer to similar parts throughout the several views, the numeral 1 indicates a support preferably integral with a nose bridge 45 2 and also having, preferably integral therewith, lens-retaining members 3 and 4. A finger-operated nose-grip-carrying lever 5 is mounted upon the support 1 and is adapted to have a pivotal movement thereon about 50 the retaining member 6 which is preferably in the form of a headed screw. This retaining member is threaded or otherwise secured in the support 1. An operating spring 7 encompasses the shank portion 8 55 of the retaining member and opposite ends

9 and 10 of the spring 7 engage, respectively, the fixed support 1, or a part thereof, and the nose-grip-carrying end of the lever 5. The shape and construction of this operating spring form very important features of 60 the present invention. It will be noted that the body portion of the spring is wound or coiled in a helical fashion, and upon reference to Fig. 4 of the drawing it will be obvious that the spring is formed of material 65 having a greater cross sectional dimension in the plane of its effective resiliency *i. e.* in the plane of the oscillation of the guard lever, than at right angles thereto, *i. e.* the plane of its axis. Heretofore springs have 70 been used in devices of this general character which were round in cross section, and accordingly for every pitch convolution at least as much space was required in a vertical direction as would equal the cross sectional diameter of the material. In actual 75 practice it has been found that where round springs were used to form the coil quite a large number of convolutions were required to furnish the necessary pressure to urge 80 the nose grip firmly against the nose. To employ such a number of convolutions required a great deal of pitch space, necessitating an extremely long shank on the retaining member and dividing the points 85 of application of power by a substantially great vertical distance.

By the present invention the shank of the retaining screw may be made very short, and by making the spring in its present 90 form, the feature of strength is not sacrificed for the reason that the spring is preferably constructed from a length of round spring wire flattened on opposite sides substantially into the shape indicated in Fig. 95 4 of the drawing. As many convolutions may be made with the spring of the present invention as might be made with the old style spring, yet it will be obvious that the pitch space required will be probably less 100 than half of that required for the old style spring. A spring is, therefore, provided having substantially the same strength and substantially the same resiliency as a round wire spring of equal cross sectional area 105 having the same number of convolutions. With the present spring, however, the retaining member may be made substantially shorter and the points of application of pressure of the opposite ends of the spring are 110

brought closer to alinement, providing a much more effective and substantial device.

In making the operating spring a length of round spring wire is flattened providing two flat sides and two curved edges. These edges are curved for the reason that the wire does not lose its round character at the edges as the pressure is applied to flatten the sides. The spring is then helically coiled flatwise on a mandrel or in any suitable manner. That is, when coiled, the edges lie in the pitch plane and the flattened sides lie substantially in the plane of the circumference.

It will be seen from the foregoing that there is provided a device which accomplishes, among others, all of the objects and advantages hereinbefore set forth.

As many changes could be made in carrying out the above method, and in the above construction, and many apparently widely different embodiments of this invention could be made without departing from the scope thereof, it is intended that all matter contained in the above description or shown in the accompanying drawing shall be interpreted as illustrative and not in a limiting sense. It is also to be understood that the language used in the following claims is intended to cover all of the generic and specific features of the invention herein de-

scribed and all statements of the scope of the invention which, as a matter of language, might be said to fall therebetween.

Having described my invention, what I claim as new and desire to secure by Letters Patent is:

1. In a device of the nature described, in combination, nose grips, and an operating spring comprising a body portion of flat resilient material convoluted flatwise.

2. In a finger piece eyeglass mounting, in combination, a movable nose grip and a positioning spring therefor of relatively greater cross-sectional dimension in the plane of its effective resiliency than at right angles thereto.

3. In a finger piece eyeglass mounting, in combination, a movable nose grip and a positioning spring therefor comprising a body portion of flattened resilient material with rounded edges wound helically, and having its cross-sectional dimension transversely of its helical axis greater than its cross-sectional dimension parallel thereto.

55

In testimony whereof I affix my signature, in the presence of two witnesses.

ANDREW J. MORRARTY.

FRANK KAY.

Copies of this patent may be obtained for five cents each, by addressing the "Commissioner of Patents, Washington, D. C."

It is hereby certified that in Letters Patent No. 1,162,184, granted November 30, 1915, upon the application of Andrew J. Morratty, of Providence, Rhode Island, for an improvement in "Eyeglass-Mountings," an error appears in the printed specification requiring correction as follows: Page 1, after line 21, insert the paragraph:

Other objects will be in part obvious and in part pointed out hereinafter.
and that the said Letters Patent should be read with this correction therein that the same may conform to the record of the case in the Patent Office.

Signed and sealed this 11th day of January, A. D., 1916.

[SEAL.]

J. T. NEWTON,

Acting Commissioner of Patents.
